UNITED STATES PATENT OFFICE.

CHARLES KITSCHELT, OF NEW YORK, N. Y., ASSIGNOR TO NICHOLAS MULLER'S SONS & CO., OF SAME PLACE.

DESIGN FOR TOILET-STAND.

SPECIFICATION forming part of Design No. 11,812, dated June 8, 1880.

Application filed May 8, 1880. Term of patent 34 years.

To all whom it may concern:

Be it known that I, CHARLES KITSCHELT, of the city, county, and State of New York, have invented a new and original Design for 5 Toilet-Stands, of which the following is a full, clear, and exact description.

The nature of my design is fully shown in the accompanying drawing, to which reference is made.

10 The invention relates to a design for a toilet-stand; and it consists of an ornamental base resting upon legs and supporting a central figure which carries a clock.

15 A in the drawing represents the supporting-base of my stand, which rests on ornamental legs *a* at the center and ends. The base is ornamented in any suitable manner, according to the character given to the entire stand.

20 A fanciful figure, B, is arranged on a skin, *b*, spread over the middle part of the base A, the figure carrying on its head and lifted arms a clock.

At each side of the central figure, B, the base A is provided with an indentation, into which a toilet-bottle, D, may be placed, the 25 whole forming a neat and striking design for a toilet-stand.

Having thus described my invention, I claim as new and desire to secure by Letters Patent—

30 The design for a toilet-stand, consisting of a supporting-base, A, provided with indentations on either side, and of a central figure, B, the latter carrying the clock, substantially as described.

35 In testimony that I claim the foregoing as my invention I have signed it this 20th day of April, 1880.

CHARLES KITSCHELT.
